TEETHER

Saul D. Horwitz, New York, N. Y.

Application January 25, 1956, Serial No. 39,911

Term of patent 14 years

(Cl. D83—1)

FIG. 1.

FIG. 2.

FIG. 3.

Fig. 1 is a front elevational view of a teether embodying my new design;

Fig. 2 is a bottom plan view taken from the underside of Fig. 1; and

Fig. 3 is an elevational view taken from the right or left of Fig. 1.

The dot dash lines show the features of a typical face. The essential features of my design reside in the portions shown in full lines.

I claim:

The ornamental design for a teether, substantially as shown and described.
